UNITED STATES PATENT OFFICE,

HUGO GERNSEY, OF NEW YORK, N. Y.

RELAY.

978,990.

Specification of Letters Patent. Patented Dec. 20, 1910.

Application filed March 14, 1910. Serial No. 549,193.

To all whom it may concern:

Be it known that I, Hugo GERNSEY, residing at New York, in the county of New York and State of New York, have invented 5 certain new and useful Improvements in Relays, of which the following is a specification.

My invention is a new and improved relay particularly designed for use in telegraphy and more particularly useful in those systems of wireless telegraphy wherein coherers and de-coherers are employed. In the systems of telegraphy referred to the great difficulty encountered in practice is to 15 provide a relay that will be sufficiently sensitive to respond to very weak impulses (such as arrives at a receiving station from sending stations a great distance away), and yet will be of an inexpensive nature, simple in 20 construction and operative under adverse conditions, such as arise in places subject to much vibration.

My invention therefore has for its object 25 to provide a relay as free from the objections noted as possible, and one which will embody the advantageous features such as extreme sensitiveness, operative under all conditions usually met with in practice and of an inexpensive construction. To this end I provide 30 a base on which a standard is mounted to which a horizontally held leaf spring is attached at one end. The standard carries an adjusting screw which bears on the spring and through which the tension of the spring 35 may be regulated and the distance between the local circuit contacts may be adjusted. The relay magnet carries one of the local circuit contacts and the armature carries the other. The armature is carried by the free end of the spring.

In its more subordinate nature, the invention 40 also embodies those novel details of construction, combination and arrangement of parts, all of which will be first fully described and then be specifically pointed out in the appended claims, reference being had to the accompanying drawings, in which:

Figure 1, is a perspective view of the invention. Fig. 2, is a central, vertical, longitudinal section thereof. Fig. 3, is an inverted, plan view of the same, showing the wiring connections.

Referring now to the accompanying drawings in which like letters and numerals 55 of reference indicate like parts in all of the

figures, 1 is the base upon which the standard 2 is mounted. The standard 2 has a heel 2^a through which bolts or screws 3 pass to secure the standard 2 to the base 1.

Secured at 5^b to the standard 2 and projecting in a substantially horizontal plane is a thin leaf spring 5 which carries the armature 5^a and holds it over the core 7^a of the electromagnet 7 that is secured to the base 1 at 7^b in the usual manner.

The standard 2 has an arm 2^b apertured and tapped at 2^c to receive the tension screw 4 whose pointed end 4^a engages the spring 5 to adjust the same. The screw 4 is provided with an insulated head 4^b, as indicated.

The armature 5^a has a platinum contact 6 to coöperate with the platinum point 7^b in the magnet core 7^a to form the local circuit make and break points.

Two sets of binding posts 8—8^a and 10—10^a are provided on the base 1, and the wires 7^a from the winding of the magnet 7 are connected to the binding posts 8—8^a.

The standard 2 is connected through a wire 9 to the binding post 10, while the core 7^a of the magnet 7 is connected through a wire 9 with the binding post 10^a. In practice, the local circuit is connected to the binding posts 10—10^a while the operating circuit is connected with the posts 8—8^a.

From the foregoing it will be observed, that the armature is horizontal and does not work against the action of gravity, but is assisted by the action of gravity in closing the local circuit. I find from practical tests that a relay constructed in accordance with my invention is from 25 to 50 per cent. more sensitive than the ordinary pony relay.

From the foregoing description taken in connection with the accompanying drawings, it is thought the complete construction, operation and advantages of my invention will be readily understood.

What I claim is:

1. A relay comprising a base, a standard mounted thereon, an electromagnet having a core also mounted on said base, a resilient member secured to said standard and projected in a horizontal plane, an armature for said magnet carried by said resilient member and held in a horizontal plane, means for adjusting the tension of said resilient member, binding posts on said base electrically connected with the winding of said magnet, another binding post on said base 100

105

110

electrically connected with the core of said magnet, and still another binding post on said base connected with said standard.

2. A relay comprising a base or support, 5 a standard mounted thereon and having a vertically disposed portion and a horizontal arm projected therefrom, a leaf spring secured to said vertical portion and held substantially in a horizontal plane, an adjusting screw carried by said arm for engaging 0 said spring, an electromagnet having a core,

an armature carried by said spring for said magnet and adapted to engage said core and circuit make and break points between said armature and said core, and means for connecting a local circuit with said standard and said core. 15
